UNITED STATES PATENT OFFICE.

CLARK A. BRENNAN, OF MINNEAPOLIS, MINNESOTA.

RAILWAY-CAR BRAKE.

Application filed December 13, 1926. Serial No. 154,404.

This invention relates to mechanism for applying the hand operated brakes on railway cars, and particularly on railway freight cars.

5 The law now requires that every railway freight car carry hand mechanism for applying the brakes thereof. The hand mechanism now commonly used for applying the brakes on such cars is both dangerous in operation to the brakeman applying the same, is very difficult to operate and is inefficient in action to properly stop the car.

It is accordingly an object of this invention to provide an improved hand operated 15 mechanism for applying the brakes on railway cars, which can be used without danger in application with great efficiency.

It is a further object of this invention to provide hand operated mechanism which 20 will utilize the motive force of a railway car when in motion to set the brakes of the car.

Yet another object is to provide hand operated mechanism which can be thrown into engagement to cause a rotating axle of a 25 moving car to set the brakes of the car.

Another object is to provide clutch mechanism on an axle of a railway car which can be thrown into engagement to cause the clutch to rotate with the axle, and means 30 for connecting the rotatable clutch with the brake rigging of a car to set the brakes thereof as the clutch is rotated.

A further object is to provide a clutch mechanism which can be thrown into engagement with the rotating axle of a railway car, the clutch mechanism having a drum carried thereon and a flexible member connected with the drum and with the brake rigging of the car to set the brakes, as the 40 same is wound upon the drum.

These and other objects and advantages of the invention will more fully appear from the following description made in connection with the accompanying drawings, 45 wherein like reference characters refer to the same or similar parts throughout the various views and, in which,

Fig. 1 is a vertical section taken on the line 1—1 of Fig. 2, as indicated by the ar-

rows, through a portion of a railway freight 50 car having one embodiment of the present invention applied thereto;

Fig. 2, is a plan view of one truck of a railway freight car showing one embodiment of the present invention applied thereto;

Fig. 3, is a horizontal section taken through the forward axle of the truck, as indicated in Fig. 2;

Fig. 4, is a section taken on the line 4—4 60 of Fig. 3, as indicated by the arrows;

Fig. 5, is a vertical section taken on the line 5—5 of Fig. 3, as indicated by the arrows;

Fig. 6, is a vertical section taken on the 65 line 6—6 of Fig. 3, as indicated by the arrows;

Fig. 7, is an end elevation of the top portion of a freight car showing a portion of the present device applied thereto;

Fig. 8, is a horizontal section taken on the line 8—8 of Fig. 7, as indicated by the arrows;

Fig. 9, is a detail view showing portions of certain of the parts used, and,

Fig. 10, is another detail view of certain of the parts of the device.

Referring to the drawings, certain parts of a freight box car of standard construction are illustrated including the rear truck of the car adjacent the brake or B-end of the car, and a portion of the box body of the car. The rear truck includes the truck bolster 11, side frames 12 of diamond type, rear axle 13, front axle 14, wheels 15 and front and rear transoms 16. A portion of the brake rigging of the car is shown including the brake beam 17, brake heads 18, and brake beam actuating rods and levers 19, 20, and 21. Lever 20 is illustrated as connected to the piston of the air brake cylinder 22, whereby as pressure is applied to the cylinder 22, pressure will be applied to the levers and rods 19, 20, and 21 to cause the brake beams 17 to set the brake heads 18 against the wheels 15 of the truck. Chains 17^a are

80
85
90
95

illustrated which will normally be connected to suitable brake hangers not illustrated.

The box body of the car includes the body bolster 23, sills 24, box body proper 25, end platform 26 and the grab iron 27, secured to the top of the car at the B-end thereof.

5 Axles 13 and 14 are of common construction, axle 14 having the conical portions 14^a immediately inside the spindle portions thereof to strengthen the axle adjacent the wheels.

10 In accordance with the present invention, a fixed member of a sliding cone clutch is provided comprising the two members 28, embracing one conical portion 14^a of the axle 14 and being secured together by bolts running through surfaced flanges thereon, one of said members 28 being splined to conical portion 14^a by key 28^a. Inwardly facing split conical surfaces 28^b are formed on the circumferential edges of members 28, each of said surfaces 28^b having secured thereto brake lining 29. Lining 29 may be formed of leather or any other suitable lining material, such as is now commonly employed in connection with automobile brakes.

15 The inner sides of each of the members 28 are cut away at 28^c to form portions of an oil and packing chamber to be hereinafter described. One of the flanges on each member 28 is provided with an upstanding or 20 tenon portion 28^d while the other flange of each member 28 is provided with a grooved or mortised portion 28^e, a tenon portion 28^d of one member 28 fitting within the mortised portion 28^e of the other member 28.

25 The sliding member of the clutch is formed by the two half members 30, the said members being secured together by bolts running through surfaced flanges thereon, each member 30 having one flange formed with a tenon 30^a and another flange with a mortise 30^b, the tenon 30^a of one member 30 engaging within the mortise 30^b of the other member 30. Members 30 are each inwardly recessed at their outer ends to form the hollow bell shaped member of the clutch, the recessed portions having outwardly facing split conical surfaces 30^c formed thereon, the said surfaces being adapted to abut the brake lining 29. The said recessed portions inwardly from conical surfaces 30^c form with the recessed portions 28^e of members 28 an oil and packing chamber. Central half hubs 30^d are formed in each of members 30, the said half hubs co-operating to form a bearing within which the shaft 14 will run. The central outer surfaces of both members 30 are contracted towards the axle 14 to form a drum 30^e upon which one end of a chain 31 or flexible cable is adapted to be wound. Ring grooves 30^f are formed on each of the perimeters of the members 30 adjacent the inner ends thereof, half rings 32 being provided which fit within the said grooves. A shifting head 33 is provided to which the half rings 32 are secured, the shifting head 33 being composed of semi-circular members secured together by bolts extending through flanges thereon. A tension spring 34 is secured at one end to an eye in the forward transom 16 and at its other end to one of the flanges of the shifting head 33. Small bosses 33^a are formed on each of the members composing the shifting head 33 at diametrically opposite points thereon. Arms 35 are pivoted to the bosses 33^a as by bolts 36 for horizontal swinging movement. The said arms 35 are preferably composed from strap iron and are twisted at right angles after being projected outwardly from bosses 33^a a short distance. The arms 33 then converge towards each other and are joined together by a socket 37 forming the forward half of the socket of a ball and socket joint. A bracket 38 is secured to the forward transom 16 adjacent the opposite side of the truck from the members 28 and 30. Bracket 38 has a plurality of holes therein whereby various adjustment of the length thereof from transom 16 may be made. A rod 39 is pivoted at one end to bracket 38 and has a ball formed at the other end thereof fitting within half socket 37. A cap 40 is bolted to half socket 37, cap 40, half socket 37 and the ball at the end of rod 39 forming a ball and socket joint. The rod 39 and arms 35 form a toggle for movement of the shifting head 33. A horizontal rib is formed at the rear side of cap 40 to which a forked end of an actuating rod 41 is secured, the rod 41 extending rearwardly from cap 40 beneath the central portion of the truck bolster 11 to adjacent the rear or brake end of the car.

35 Bearing blocks 42 are secured in vertical alignment to the brake end of the car body at spaced points, one of the blocks being secured preferably to the end sill 24 and the other block being secured to the body proper 25 adjacent the top thereof. A crank arm 43 having a spool thereon fitting within the lower bearing block 41 is provided, the spool having a square aperture cut part way therethrough within which fits the lower square end of a vertical staff 44. The rear end of the actuating rod 41 is forked to receive the outer end of crank arm 43, the crank arm 43 and actuating rod 41 being pivoted together. A strap bearing 45 extends around the central portion of the spool on arm 43, the strap bracket being secured by bolts to the lower block 42. Staff 44 extends upwardly from crank arm 43 through the bearing portion of the upper bearing block 42. A lever 46 having a spool, the central portion of which fits within the upper bearing block 42, is secured to staff 44 at the upper end thereof, the staff being squared at its upper end and fitting within a square bore extending partially through the spool in lever 46. A ratchet 47 forming a strap bear-

40 45 50 55 60 65 70 75 80 85 90 95 100 105 110 115 120 125 130

ing within which the spool of lever 46 is secured, is itself bolted to the upper bearing block 42. A dog 48 pivoted adjacent the lower end of lever 46 is adapted to fit in any of the ratchet teeth on ratchet 47. A bar spring 49 secured to lever 46 normally urges the dog 48 into engagement with the ratchet teeth. A bell crank handle lever 50 is pivoted to the outer end of lever 46, an actuating rod 51 being pivoted at one end to one of the lever arms of handle lever 50 and pivoted at its other end to the dog 48. Ratchet 47 has a plurality of ratchet teeth 47^a adapted to hold the dog 48 in engagement to prevent rotation of the lever 46 in one direction and a single tooth 47^b adapted to hold dog 48 in engagement therewith to prevent lever 46 being swung in an opposite direction.

One of the members 30 of the shifting portion of the clutch is provided outwardly from the central portion of its hub portion 30^d with an aperture extending through one wall of the drum 30^e and partially through the other wall thereof. A pin 52 is inserted within said aperture, the pin being held from removal by a cotter-pin secured in spaced ears 30^g formed at the inner side of the chosen member 30. A short chain 53 is preferably secured to the rear end of the piston in the air cylinder 22, the chain having secured thereto at its end, pulley block 54 within which pulley wheel 55 is journaled. A chain 31 is secured at one end to pin 52, the chain running through the pulley block 54, about pulley wheel 55 and being secured at its other end to an eye secured to a portion of the car body as the sill 24. A plug 56 is provided in one of the members 30, the plug leading to the oil and packing chamber formed between the recessed portions of members 30 and the recessed portions 28^c in members 28.

Operation.

The parts of the device will normally stand when a railway car is in travel with the sliding member of the clutch formed by members 30 slid inwardly from the fixed member of the clutch formed by members 28. In such position, there will be no engagement between the conical surfaces 30^e and the brake lining 29, and the lever 46 will stand in the position indicated in Fig. 8 with the dog 48 in engagement with the first notch in the ratchet 47 to prevent movement of lever 46 to the left.

When it is desired to apply the hand brake on the car, the brakeman will stand upon the end platform 26, grasp the grab iron 27 with his left hand and grasp the end of the lever 46 and the bell crank handle lever 50 with his other hand. If he is carrying a lantern in his right hand, the same may be held while levers 46 and 50 are

grasped. Hand lever 50 will now be moved towards the lever 46 thereby raising the dog 48 against the tension of spring 49 to swing the dog outwardly from tooth 47^b of ratchet 47. Lever 46 will now be swung to the left of the position shown in Fig. 7. Staff 44 will accordingly be turned, thereby swinging arm 43 towards the rear truck of the car. Rod 41 will accordingly be actuated to spread the toggle arms 39 and 35. 75 Arm 39 being pivoted to the fixed bracket 38, all the movement of the toggle connection will be transmitted to move the operating head 33 to the left, as illustrated in Figs. 3 and 4, thereby shifting the sliding member of the clutch formed by members 30. The sliding member of the clutch will accordingly be thrown into engagement with the fixed member of the clutch, the surfaces 30^e of the sliding member gripping the 85 brake lining 29. The car being in motion and axle 14 rotating under tremendous power, the shifting member of the clutch will be rotated with the fixed member and with the axle 14. As the shifting member 90 of the clutch rotates, chain 31, secured to the shifting member by the pin 52, will be wound on the drum 30^e, accordingly, pulling the pulley wheel 55, pulley block 54 and chain 53 towards the axle 14 with tremendous power. Chain 53 being secured to the same brake rigging as is the piston of the air cylinder 22, the brakes will be set against the wheels 15 of the car to skid the same. The car will, accordingly, be quickly stopped 100 in transit by exerting but slight power upon the lever 46. After the lever 46 has been carried to the left to engage the two members of the clutch, spring 49 will force the dog 48 downwardly into engagement with one of the ratchet teeth 47^a to hold the clutch members in engagement. Accordingly, after the car has been brought to a stop the two members of the clutch still remain in engagement to anchor the car. The car when 105 so anchored, will, of course, be capable of limited movement in an opposite direction from which it was originally running but this movement will only be that of double the length of the portion of chain 31 wound upon the drum 30^e. The present device will not interfere with the independent air brake system of the car to set the brakes nor will the air brake system interfere with the action of the present device.

When now it is desired to release the hand brake on the car, lever 46 and hand lever 50 will be grasped, whereupon lever 46 will be swung to the position indicated in Figs. 7 and 8, the dog 48 first being disengaged from the ratchet teeth 47^a. The shifting member of the clutch will thus be slid on axle 14 away from the fixed member of the clutch to disengage the conical portions 30^e from the brake lining 29. The chain 31 130

will either unwind from the drum 30° due to its own weight or will soon unwind therefrom, due to the jolting of the car, as it is first set in motion.

Spring 34 holds the actuating head 33 from rotation with the slideable member of the clutch and preferably the end of spring 34 connected to the forward transom 16 is secured to an eye secured inwardly from actuating member 33 when the two members of the clutch are in engagement. Spring 34 will accordingly tend to draw actuating head 33 centrally of axle 14. The universal joint formed by half socket 37, rod 39 and cap 40 will permit movement of the truck in respect to the body of the car in both vertical and horizontal planes without injury to the various parts of the device. As rod 41 will normally stand directly below the central portion of the truck bolster 11, rod 41 will form but a short forward lever arm from the pivoted portion of the truck; movement of toggle arms 35 and 39 then will be but slight as the truck turns in respect to the car body. The movement of the toggle arms accordingly will be insufficient to shift the sliding portion of the clutch into engagement with the fixed portion thereof to set the brakes. The mortise and tenon connections between the flanges on members 28 and 30 will insure proper alignment of said respective members and prevent the bolts securing the various flanges together being sheared off at any time. Inasmuch as a chamber is formed between the recessed portion 28° of the fixed member of the clutch, and the recessed portion formed in the members 30 of the sliding member of the clutch, proper lubrication can be applied to the axle to insure the sliding member of the clutch being readily slid to and from the fixed member thereof.

Due to the split construction of the various parts fitting around the axle 14 of the device, it can be seen that the various parts can be readily applied to trucks which are already assembled without the necessity of disassembling the same. Accordingly, the device can be readily applied to rolling stock now in use.

It will, of course, be understood, that the drawings illustrate but one embodiment of the invention applied to but one type of railway car. The device can be applied on any type of railway car, whether using inside or outside brakes by slightly changing the location and arrangement of certain parts. Various types of mechanism may be substituted for the operating rod 41 and toggle arms 39 and 35 for shifting the operating head 33. The inventor also contemplates the use of different types of clutch mechanism than that above described and illustrated.

It will, of course, be understood that other

changes may be made in the form, details, arrangement and proportions of the various parts without departing from the scope of the present invention, which, generally stated, consists in the matter shown and described and set forth in the appended claims.

I claim:

1. The combination with a railway car and the axle and brake rigging thereof, of a brake actuating mechanism, comprising a fixed clutch member secured to said axle, a sliding clutch member journaled on said axle for sliding engagement with said fixed member, said sliding clutch member having a drum formed thereon, a flexible member connected at one end to said drum and at its other end to said brake rigging, said flexible member being adapted to operate said brake rigging to set the brakes as said flexible member is wound on said drum, a shifting head for shifting said sliding clutch member, a toggle arm connected at one end to said shifting head, a toggle arm having one end pivoted to a fixed bracket, said toggle arms being connected together by a universal joint, an actuating rod pivoted to said universal joint and means connected to said actuating rod for moving the same.

2. The combination with a railway car and the axle and brake rigging thereof, of a brake actuating mechanism comprising a member adapted to be engaged with said car axle to rotate therewith, said member having a drum formed thereon, a flexible member connected to said drum and to said brake rigging, a toggle adapted to be operated to throw said first mentioned member into engagement with said car axle when said axle is rotating, thereby rotating said first mentioned member and causing said flexible member to wind on said drum to operate said brake rigging to set the brakes, an actuating rod for operating said toggle, a staff at the end of the car having a crank thereon for moving said rod and means adapted to be operated to turn said staff.

3. The combination with a railway car and the axle and brake rigging thereof, of a brake actuating mechanism comprising a member adapted to be engaged with said car axle to rotate therewith, said member having a drum formed thereon, a flexible member connected to said drum and to said brake rigging, a toggle adapted to be operated to throw said first mentioned member into engagement with said car axle when said axle is rotating, thereby rotating said first mentioned member and causing said flexible member to wind on said drum to operate said brake rigging to set the brakes, an actuating rod for operating said toggle, a staff at one end of the car having a crank thereon for moving said rod, a lever for

turning said staff, a ratchet adjacent said lever and a dog secured to said lever for engagement with anyone of the teeth of the said ratchet.

- 5   4. The combination with a railway car axle and brake rigging, of a fixed clutch member secured to said axle, a sliding clutch member journaled on said axle for engagement with said fixed clutch member,
10   said clutch members having opposing faces with hollowed out portions therein to form

an oil and packing chamber for lubricating purposes, a flexible member adapted when pulled to actuate said brake rigging to set the brakes and means for throwing said 15 clutch members into engagement to cause said flexible member to be wound on said movable member of the clutch to set the brakes of the car when the same is in motion.

In testimony whereof I affix my signature.

CLARK A. BRENNAN.
